CLAIM

The ornamental design for an inverter module, as shown and described.

DESCRIPTION

FIG. 1 is a top view of an inverter module showing a new design;

FIG. 2 is a bottom view of an inverter module showing a new design;

FIG. 3 is a first side view of an inverter module showing a new design;

FIG. 4 is a second side view of an inverter module showing a new design;

FIG. 5 is a third side view of an inverter module showing a new design;

FIG. 6 is a fourth side view of an inverter module showing a new design; and,

FIG. 7 is a top-perspective view of an inverter module showing a new design.

The broken line portion of the figure drawings is included to show unclaimed subject matter only and forms no part of the claimed design.
